UNITED STATES PATENT OFFICE.

JOHN MCMURTRY, OF MISSION, TEXAS, ASSIGNOR OF ONE-THIRD TO W. H. PARKS AND ONE-THIRD TO A. H. STRAHLER, BOTH OF MISSION, TEXAS.

RAILWAY SWITCH.

Application filed December 28, 1927. Serial No. 243,191.

This invention relates to railway switches and has for an important object thereof the provision of a frogless continuous rail switch.

- 5 A further object of the invention is to provide in a device of this character a construction such that it may be applied to a right-of-way without in any way cutting or interrupting the same.
- 10 A still further object of the invention is to produce a structure such that the switching elements are only supported at the cross-over point.

15 A further and more specific object of the invention is the provision in a device of this character of a construction, wherein tapered rails are employed to raise the level of the switch to such a point that where a cross-over occurs, a relatively heavy switch rail section may be used, so that an adequate support will be provided at the cross-over point during the switching operation.

20 These and other objects I attain by the construction shown in the accompanying drawings, wherein for the purpose of illustration is shown a preferred embodiment of my invention and wherein:—

25 Figure 1 is a plan view showing switch mechanism constructed in accordance with my invention, the switch points being indicated in solid lines in inoperative position and in dotted lines in switching position;

Figure 2 is a section on the line 2—2 of Figure 1;

30 Figure 3 is a section on the line 3—3 of Figure 1;

Figure 4 is a section on the line 4—4 of Figure 1;

35 Figure 5 is a section on the line 5—5 of Figure 1.

Referring now more particularly to the drawings, the numerals 10 and 11 indicate the rails of a right-of-way, which may be of any usual or preferred construction. In accordance with my invention, I associate with the rails 10 and 11 pivoted switch points 13 and 14, of which the switch point 13 is constructed to overlie the rail 10 and the switch point 14 to abut against the rail 11.

40 Each of the switch points 13 and 14 is of considerable length and is tapered throughout its length. In the case of the switch point 13, the portion thereof which overlies the rail 10 when in switching position is

45 wedge-shaped increasing in thickness from a

thin tip portion to a point where it is of a thickness greater than the depth of the flange of the rail. From this point on, the switch point 13 begins to diverge from the rail to the point of its pivotal connection to the switch track rail 15. The switch point 14 may be somewhat shorter than the switch point 13 and, except for its taper, constructed after the manner of constructing ordinary inside switch points. The switch point 14 is pivoted at its end to the inside switch track section 16.

50 At the cross-over connection between the inside switch track 16 and the rail 10, I employ a base 17 having castings 18 and 19 mounted thereon, this base extending beneath the cross-over connection and to the outside switch rail 15, where it supports a guard rail 20. The casting 18 has at its forward end a slot 21 receiving and fitting the web and base of the inner end of the switch track section 16, and has its upper surface 22 arranged in the same plane as the under surface of the head 23 of the switch rail section 16 and the upper surface of the head of the main track rail 10. At the included angle between the casting 18 and rail 10, the casting is provided with a projection 24 forming a filler block engaging the rail 10. Upon its upper surface adjacent its outer face, the casting 18 is provided with an upstanding rib 25, the inner face of which forms a continuation of the outer face of the head 23 of the rail 16.

55 The casting 19 is constructed to fit against the outer face of the web of the rail 10, and has its upper surface arranged in the same plane as the upper surface of the head of the rail 10. At its inner end, this casting is formed with a socket receiving the outer end of a second section 16^a of the inside switch rail 16. Pivoted to the upper surface of this casting at 26 is a cross-over switch point 27 adapted to swing from a position where it substantially parallels the head of the rail 10 and lies outwardly thereof to a position where it extends across the head of the rail 10, has its free end in engagement with the inner face of the rib 25 of the casting 18 and bridges the gap between the heads of the rail sections 16 and 16^a of the inner switch rail.

60 To insure against striking of the switch point 27 against the head of the rail 10

during its movement from the first or inoperative to operative position, I provide upon the upper surface of the casting 19 a cam ridge 28 over which the switch point passes and 5 by which the switch point is lifted during the time when it would come into engagement with the rail head. To insure a sufficient thickness of the bar forming the switch point 27 to withstand the stress to which it 10 is subjected during passage of a train there-over, the rail section 16 and its head 23 may increase in vertical depth as they approach the casting 18. The section 16 may be correspondingly tapered in the opposite direction 15 to bring the track to the normal size. Under these circumstances, it will, of course, be understood that the rail 15 must be given a similar taper.

The operation of the switch points 13, 20 14, and 27 will, of course, be simultaneous and any suitable means may be provided to effect their operation. In the present instance, I have shown a standard switch stand 29 connected in the usual manner to the 25 points 13 and 14 and provided with an additional arm 30 connected through a bell crank 31 and links 32 and 33 with the switch point 27. Toe guards for the switch points 13 and 27 may be provided, as indicated at 34 and 35, the latter being shown as mounted upon the base 17. A heel guard for the switch point 27 may likewise be provided and in case it is provided, this guard is mounted upon the casting 19, as shown at 36. 30 Since the construction hereinbefore set forth is capable of a certain range of change and modification without materially departing from the spirit of the invention, I do not limit myself to such specific structure 35 except as hereinafter claimed.

I claim:

1. A frogless cross-over switch mechanism comprising in combination with the main rails of a right-of-way, tapered switch 45 points for coaction therewith one of which is arranged outwardly of the associated rail and when in switching position overlies the rail, a pair of castings arranged upon opposite sides of said rail at points spaced from 50 said switch point, said castings having their upper faces co-planar with the head of the rail, a rail section connected to the other of said switch points and extending to the casting disposed between the rails, the head of 55 said rail section extending above the upper surface of the casting, a second rail section secured to the other of said castings and aligning with the first named rail section, the second rail section likewise having its 60 head extending above the surface of its casting, a switch point pivoted to the last named casting and movable from a position where it parallels said main rail of the right-of-way to a position where it extends over 65 said main rail and bridges the gap between

the heads of said rail sections and means upon one of the castings engaging the outer face of said switch point to limit movement thereof when in the last named position.

2. A frogless cross-over switch mechanism comprising in combination with the main rails of a right-of-way, tapered switch points for coaction therewith one of which is arranged outwardly of the associated rail and when in switching position overlies the rail, a pair of castings arranged upon opposite sides of said rail at points spaced from said switch point, said castings having their upper faces co-planar with the head of the rail, a rail section connected to the other of said switch points and extending to the casting disposed between the rails, the head of said rail section extending above the upper surface of the casting, a second rail section secured to the other of said castings and aligning with the first named rail section, the second rail section likewise having its head extending above the surface of its casting, and a switch point pivoted to the last named casting and movable from a position where it parallels said main rail of the right-of-way to a position where it extends over said main rail and bridges the gap between the heads of said rail sections, the last named switch point when in switching position being supported at its ends by said casting and intermediate its ends by the head of said main rail.

3. A frogless cross-cover switch mechanism comprising in combination with the main rails of a right-of-way, tapered switch points for coaction therewith one of which is arranged outwardly of the associated rail and when in switching position overlies the rail, a pair of castings arranged upon opposite sides of said rail at points spaced from said switch point, said castings having their upper faces co-planar with the head of the rail, a rail section connected to the other of said switch points and extending to the casting disposed between the rails, the head of said rail section extending above the upper surface of the casting, a second rail section secured to the other of said castings and aligning with the first named rail section, the second rail section likewise having its head extending above the surface of its casting, a switch point pivoted to the last named casting and movable from a position where it parallels said main rail of the right-of-way to a position where it extends over said main rail and bridges the gap between the heads of said rail sections, and means upon said other casting coacting with the last named switch point to elevate the same during its movement from the first to the last named position.

4. A frogless cross-over switch mechanism comprising in combination with the main rails of a right-of-way, tapered switch

- points for coaction therewith one of which is arranged outwardly of the associated rail and when in switching position overlies the rail, a pair of castings arranged upon opposite sides of said rail at points spaced from said switch point, said castings having their upper faces co-planar with the head of the rail, a rail section connected to the other of said switch points and extending to the casting disposed between the rails, the head of said rail section extending above the upper surface of the casting, a second rail section secured to the other of said castings and aligning with the first named rail section, the second rail section likewise having its head extending above the surface of its casting, a switch point pivoted to the last named casting and movable from a position where it parallels said main rail of the right-of-way to a position where it extends over said main rail and bridges the gap between the heads of said rail sections, the first named rail section increasing in height from the switch point to the casting with which it is associated, the last named rail section decreasing in height from the point of its attachment to the casting with which it is associated, and a further rail section secured to the first named switch point and increasing in height from said switch point to a point opposite the casting.
5. A frogless cross-over switch mechanism comprising in combination with the main rails of a right-of-way, tapered switch points for coaction therewith one of which is arranged outwardly of the associated rail and when in switching position overlies the rail, a pair of castings arranged upon opposite sides of said rail at points spaced from said switch point, said castings having their upper faces co-planar with the head of the rail, a rail section connected to the other of said switch points and extending to the casting disposed between the rails, the head of said rail section extending above the upper surface of the casting, a second rail section secured to the other of said castings and aligning with the first named rail section, the second rail section likewise having its head extending above the surface of its casting, a switch point pivoted to the last named casting and movable from a position where it parallels said main rail of the right-of-way to a position where it extends over said main rail and bridges the gap between the heads of said rail sections, means upon one of the castings coacting with the switch point during its movement from the first to the last named position to elevate the same, and means upon the other of the castings for engaging the outer face of the switch point to limit its movement when in the last named position.
- 10 15 20 25 30 35 40 45
- the second rail section likewise having its head extending above the surface of its casting, and a switch point pivoted to the last named casting and movable from a position where it parallels said main rail of the right-of-way to a position where it extends over said main rail and bridges the gap between the heads of said rail sections, the first named casting having a rib against which the outer face of the last named switch point engages when in the last named position.
- 55 60 65 70 75 80 85 90
6. A frogless cross-over switch mechanism comprising in combination with the main rails of a right-of-way, tapered switch points for coaction therewith one of which is arranged outwardly of the associated rail and when in switching position overlies the rail, a pair of castings arranged upon opposite sides of said rail at points spaced from said switch point, said castings having their upper faces co-planar with the head of the rail, a rail section connected to the other of said switch points and extending to the casting disposed between the rails, the head of said rail section extending above the upper surface of the casting, a second rail section secured to the other of said castings and aligning with the first named rail section, the second rail section likewise having its head extending above the surface of its casting, a switch point pivoted to the last named casting and movable from a position where it parallels said main rail of the right-of-way to a position where it extends over said main rail and bridges the gap between the heads of said rail sections, means upon one of the castings coacting with the switch point during its movement from the first to the last named position to elevate the same, and means upon the other of the castings for engaging the outer face of the switch point to limit its movement when in the last named position.
- 70 75 80 85 90
- In testimony whereof I hereunto affix my signature.

JOHN McMURTRY.
